UNITED STATES PATENT OFFICE.

BENJAMIN L. BOLLAND, OF DETROIT, MICHIGAN.

SWITCH-CONTROLLED BATTERY.

Application filed October 25, 1923. Serial No. 670,748.

To all whom it may concern:

Be it known that BENJAMIN L. BOLLAND, a subject of the King of England, residing at Detroit, in the county of Wayne and State of Michigan, has invented new and useful Improvements in Switch-Controlled Batteries, of which the following is a specification.

The present invention has for its purpose to provide, in a switch-controlled battery, a construction particularly adapted for use in connection with radio machines and the like where the switch is carried by the battery so that it is always convenient for operation.

Another purpose is to provide a switch-controlled battery wherein the voltage thereof is variable.

It is a further purpose to provide a switch wherein the base-board thereof is embedded or countersunk in the composition, such as wax, rubber or other material, so that the base-board is flush with the surface of the composition and so that the wires or connections between the various switch terminals and the battery terminals are likewise embedded in the composition in order to prevent their disconnection and also avoid damage.

The invention comprises further features and combinations of parts to be hereinafter set forth, shown in the drawings and claimed.

In the drawings:

Figure 1 is a view in perspective of the improved switch-controlled battery constructed in accordance with the invention.

Figure 2 is a sectional view through the same, showing the various cells and their connections.

Figure 3 is a plan view with portions of the composition, such as wax or the like, broken away to show the leads and the connections with the switch.

Figure 4 is an enlarged sectional view through one face of the battery to show the mounting of the base-board of the switch.

Referring to the drawings, 1 designates the battery as a whole, preferably of the dry type. The battery includes an outer protecting casing of any suitable material 2, such as imitation leather fibre or the like, which encloses the body of composition 3, such as rubber or wax composition or the

like, in which the usual construction of battery cells are arranged. These cells are connected consecutively so as to operate to increase or decrease the voltage, it depending entirely upon the position of the switch with reference to the switch terminals.

The various cells are in circuit by means of the leads 4 with the terminals 5, 6, 7, 8 and 9. These terminals are countersunk in the wax body or composition and are in circuit by means of the leads or wires 10 with the switch terminals 11, 12, 13, 14 and 15. The switch includes a dead terminal 16. These terminals are carried by a base plate 17 of insulating material which is embedded in a countersink 18 formed in the wall of a depression 19 constructed in the composition.

A suitable knob 20 is mounted upon the base plate, there being a spring 21 for tensioning the knob to retain the switch arm 22 which is carried by the knob in engagement with any one of the terminals 11 to 15, inclusive. The knob is connected to a binding post 23 by means of a lead 24, said binding post 23 being adapted for connection with any suitable apparatus, such as a radio machine (not shown), for supplying current thereto. One of the cells at one end of the battery is connected by a wire or lead 25 with a binding post 26 which, in turn, is also adapted to be connected to the machine to which current is to be supplied.

Obviously, when the knob is rotated, the switch arm being normally engaged with the dead terminal 16, the arm passes from the dead terminal to the switch terminal 11, in which case a circuit from one of the cells of the battery to the switch terminal 11 and back to the battery is established, the voltage being of minimum power. Obviously, as the switch arm passes from one switch terminal to another until it engages the switch terminal 15, the voltage correspondingly increases consistent with the added power derived from the consecutive cells as the switch arm moves.

The invention having been set forth, what is claimed is:

In a switch controlled battery, the combination with a protecting casing, enclosed cells and a composition covering for the cells, of a base plate of insulating material embedded in said covering and having its

upper face flush with the top of the latter, an angularly movable switch arm carried by the base plate, contact terminals carried by the base plate and electrically connecting with selected cells of the battery, the cells being connected in series, and binding posts mounted in the composition covering, one

of said binding posts being connected with the terminal cell of the series and the other electrically connected with said switch arm. ¹⁰

In testimony whereof he affixes his signature.

BENJAMIN L. BOLLAND.
